UNITED STATES PATENT OFFICE.

ROYAL A. HAWLEY, OF GRAHAM, TEXAS, ASSIGNOR OF ONE-THIRD TO AGUSTUS B. EDDLEMAN AND ONE-THIRD TO WALTER B. DOUGLAS, BOTH OF GRAHAM, TEXAS.

GATE OR DOOR CLOSING DEVICE.

1,231,526.

Specification of Letters Patent. Patented June 26, 1917.

Application filed February 28, 1917. Serial No. 151,524.

To all whom it may concern:

Be it known that I, ROYAL A. HAWLEY, a citizen of the United States, residing at Graham, in the county of Young and State 5 of Texas, have invented certain new and useful Improvements in Gate or Door Closing Devices; and I do hereby declare the following to be a full, clear, and exact description of the invention, such as will enable others skilled in the art to which it appertains to make and use the same.

This invention relates to improvements in closing devices for doors, gates and the like, and the object of the invention is the provision of a device of this nature including a contractile spring, and novel, simple and efficient means for connecting the spring in operative position to a door and door frame, or to a gate and gate post.

Other objects will appear and be better understood from that embodiment of my invention of which the following is a specification, reference being had to the accompanying drawings forming a part thereof, 25 in which:

Figure 1 is an elevation of a swinging gate, with the improved closing device associated therewith.

Fig. 2 is a top plan view of Fig. 1, and 30 Fig. 3 is a detail plan view of the gate post, showing the manner of connecting one end of the spring to the gate post.

Referring to the drawings in detail, the letter A designates, for conventional purposes, a swinging gate, and the letter B designates a pair of opposed gate posts, to one of which the gate A has hinge connection. Mounted on that gate post that has hinge connection with the gate is a 35 bracket including a horizontally disposed arm 1, one end of which is provided with a flanged head 2, the said head 2 being secured to the adjacent gate post in any suitable manner. The arm 1 is provided with a threaded portion 3, which is threadedly received by one end of a contractile helical spring 4. The opposite end of the helical spring 4 has the terminal thereof extended horizontally, as shown at 5, and thence bent 40 to form an eye 6, which slidably receives a

horizontal rod 7. The rod 7 is associated with the gate A, and has its opposite ends bent into parallelism, as shown at 8, and received by openings in plates 9 that are secured to the gate A.

When the gate A is swung outwardly the eye 6 will slide along the rod 7, in a direction toward the hinged end of the gate A, and the outer end of the spring 4 will be flexed laterally from a point at the outer end 60 of the rod 1, and tensioned so that when the gate is released from open position, the spring will return to normal and effect closing of the gate. Owing to the sliding connection between the outer end of the spring, 65 and the rod 7, the tension of the spring 4 from the time the gate is initially opened, to the time that it reaches its maximum open position, will be constant.

The convolutions of the spring serve as 70 threads for coöperating with the threaded portion 3 on the arm 1 and holding the spring 4 in position on the bracket, and by virtue of this particular connection between the spring and the arm 1, the spring can 75 be adjusted in a direction toward or away from the adjacent gate post B when desired.

It is evident that various changes might be resorted to in the construction, form and 80 arrangement of the several parts without departing from the spirit and scope of the invention as claimed.

Having thus described my invention what I claim as new, is:

The combination with a hinged closure and a support therefor, of an arm carried by the support and having a threaded portion, a coil spring having one end receiving the threaded portion of the arm and having 90 its opposite end provided with an eye, and a rod carried by the closure and slidably received by the eye on the last-mentioned end of the spring, for the purpose specified.

In testimony whereof I affix my signature 95 in presence of two witnesses.

ROYAL A. HAWLEY.
